[57] CLAIM

The ornamental design for a device for adapting a sander to be a vacuum, as shown and described.

DESCRIPTION

FIG. 1 is a perspective view of the device for adapting a sander to be a vacuum embodying the design of the present invention;

FIG. 2 is a front end elevational view thereof;

FIG. 3 is a rear end elevational view thereof;

FIG. 4 is a side elevational view thereof;

FIG. 5 is a side elevational view thereof;

FIG. 6 is a top plan view thereof; and,

FIG. 7 is a bottom view thereof.

FIG. 1

FIG. 2

FIG. 3

FIG. 6

FIG. 7

FIG. 4

FIG. 5
